PORTABLE SERVICE TRAY

Melvin H. Nussbaum, Bainbridge, Ga.

Application May 13, 1933, Serial No. 670,970

1 Claim. (Cl. 311—22)

This invention relates to portable service trays; and, more particularly, one designed to be used either on the inside or outside of a vehicle window.

The principal object is to provide a tray which may be supported by the vehicle window either on the inside or outside without in any way interfering with the raising or lowering of the same. With the advent of "curb service" service trays adapted to be rested on the sill of the vehicle on which drinks and food can be placed have come into general use. The simplest form of such tray consists in supports or legs spaced apart so as to straddle the sill. The tray rests on the sill, and, of course, prevents the window from being raised or lowered. Such trays are objectionable in that the diameter of the sill varies and often presents an uneven surface so that drinks are spilled on the tray, damaging the food and making an unsightly appearance. Further, such construction makes it impossible to raise the window in case of inclement weather.

Another object is to provide means for securing the tray in position quickly and at the same time to compensate for a variance in thickness and diameter of the sill, and further, to provide means correcting the slant or tilt of the tray, the operating means to be on or above the horizontal plane of the tray and readily accessible from the exterior of the automobile or other vehicle.

Still another object is to provide a tray adapted to be used for either an open or closed vehicle.

Other objects will be disclosed in the specification and drawing forming a part of this application.

In the drawing:

Figure 1 is a fragmentary perspective of an automobile, showing the tray;

Figure 2 is a fragmentary detail of the support and locking means removed from the tray;

Figure 3 is a side elevation of the service tray showing a fragmentary sectional portion of the vehicle on which the tray is supported; and

Figure 4 is an enlarged detail of the pivoted support.

Referring to the drawing in which similar parts are designated by like numerals:

Numerals 5 designates a motor vehicle of the closed type having window sills 6, with sliding windows 7. A tray 8, constructed of metal or any other suitable material, and having rigidly secured in parallel spaced relation transversely across the underface thereof a pair of metal supports 9, one end of each of which is bent down-

wardly at right angles to afford a supporting leg 10, while the other end of each of the supports 9 is bent downwardly at 11 to form a spring arm 12, the end of which is bent at right angles to afford a clamping leg 13. An intermediate leg 14 is placed on each support 9 and fixedly secured thereto. Affixed by rivets or other suitable means to the underface of the tray 8, near the middle portion of one side thereof, is a U-shaped angle bracket 15, the two projecting arms 16 and 17 of which are positioned opposite one another in spaced relation and support a pin 18. Pivotally mounted on said pin 18 is an adjustable supporting arm 19, the pivoted end of which is formed with a cam face 20, by bending that portion of the arm 19 which projects beyond the pin 18, and the other end having a rubber cup 20'.

Slidably mounted in a bracket 21 is a bar 22 having one end upturned to form a handle 23, and the other end 24 bent at 24' in a downward direction beneath the cam 20 with an upturned portion 25 adapted to ride on the base portion 28 of the U-shaped angle bracket 15.

As actually used, the tray with its contents will be placed over one of the sills 6, the leg 13 being inserted between the sill and the window 7, the tray assuming a level position, after which the bar 22 is pulled outwardly through the bracket 21 by way of handle 23. Since the portion 24 is wedge shaped, and bears against the cam face 20, the arm 19 will be forced against the side of the car and locked in position, said arm 19 acting as a brace or support. Since the arm 19 is pivotally mounted on the pin 18, it will normally assume a perpendicular position, as shown in dotted lines 35 in Figure 3, and will be out of the way during the securing process until the handle 23 is operated.

It is obvious that the clamping leg 13 may be inserted over the other sill 6 and the tray placed on the inside of the car when desired, which permits the window to be raised if desired; or the clamping leg 13 may be placed over both sills, or in the case of an open car, over the door and arranged either inside or outside of the car. The legs 10 and 14 have no particular function other than in packing the trays for shipment they space the same apart and permit one tray to be piled upon the other, and should it be desired to place the tray on the counter while the order is being filled, the same will be level.

From the foregoing description, it is obvious that a very simple efficient construction has been produced, wherein the operator need not place

his hands inside of the vehicle except to place the tray in position, the locking handle being readily accessible and above the edge of the tray. Furthermore, only one hand is required to lock the tray in position. In other devices where the locking feature is beneath the tray, the operator must place the tray in position, steady the same with one hand and reach beneath the tray to locate the locking mechanism with the result that the contents of the tray is often spilled, or the tray is locked at an angle as the eyes of the operator must be taken from the tray.

It must be understood that the invention is not limited to the precise details or construction shown in the drawing, as many of the elements may be varied in shape or replaced by other elements performing the same or similar function, without departing from the spirit of the invention, the scope of which is defined in the claim appended hereto.

What I claim is:

A vehicle service device comprising a tray, parallel spaced supports on the underside of said tray and extending beyond one of the edges thereof, said supports having a clamping leg at the end extending beyond the edge of said tray, a U-shaped bracket secured to the underside of said tray intermediate said supports, a supporting arm pivotally mounted in said bracket and having a cam face formed at one end adjacent said pivotal point, the other end having a cup adapted to contact with a vehicle wall, a flat bracket secured adjacent the U-shaped bracket, a locking bar slidably mounted in said flat bracket and having a wedge-shaped end with one face parallel to the base of the U-shaped bracket, the other face adapted to contact with the cam face of the support tapered inwardly, the outer end of said locking bar turned upwardly to form a handle.
